METHOD OF MAKING FLAT BELTS.

No. 401,643.

Patented Apr. 16, 1889.

UNITED STATES PATENT OFFICE.

ROBERT DICK, OF GREENHEAD, GLASGOW, COUNTY OF LANARK, SCOTLAND.

METHOD OF MAKING FLAT BELTS.

SPECIFICATION forming part of Letters Patent No. 401,643, dated April 16, 1889.

Application filed July 9, 1887. Serial No. 243,902. (No model.) Patented in England October 14, 1885, No. 12,254, and June 25, 1887, No. 9,043.

To all whom it may concern:

Be it known that I, ROBERT DICK, a subject of the Queen of Great Britain and Ireland, and residing at Greenhead, Glasgow, in the county 5 of Lanark, Scotland, have invented certain Improvements in the Manufacture of Belts or other Bands, (for which I have obtained British Patents No. 12,254, dated October 14, 1885, and No. 9,043, dated June 25, 1887,) of which 10 the following is a specification.

My invention comprises a new or improved mode of making composite flat belts or bands of canvas and gutta-percha suitable for driving machinery and other purposes, and either 15 with or without a layer of woolen serge or elastic material on their working or gripping surfaces when used for driving purposes.

Figure 1 on Sheet 1 shows a sectional elevation, and Fig. 2 a plan or horizontal section, 20 taken on the irregular line 11 in Fig. 1, of the machine or arrangement of mechanism for coating the canvas, A, in web with gutta-percha solution, first on one side and then on the other, while passing it through the machine 25 at two different operations for making the belts out of such prepared webs, with a great part of the machine shown as broken away at 2 2 and 3 3 to enable it to be shown in the drawings. Figs. 3 and 4 on Sheet 2 show a 30 side elevation and corresponding plan, both partly in section, at the heating-box and fire, while a part of the length of the machine is shown as broken away at 4 4 to enable it to be shown in the drawings, all for bending or 35 folding the belts out of the various thicknesses of the canvas as prepared from the first machine shown in Figs. 1 and 2. Figs. 40 5 and 6 show a transverse section and an end elevation, respectively, drawn to a large scale, of the front part of the machine shown in Figs. 45 3 and 4, for folding and rolling and pressing the canvas into the width and thickness of belt desired, while Figs. 7, 8, and 9 are an end and a side sectional elevation and plan, respectively, of a machine for cutting the webs 50 of canvas and gutta-percha as prepared in the machine shown in Sheet 1 into strips of the proper width for being folded and pressed into the thickness and width of the belts required while passing through the arrange-

ment of mechanism shown in Figs. 3 to 6 of Sheet 2 of the drawings.

Referring to the drawings, my invention consists in forming composite belts or flat bands from canvas or strong woven cotton fabrics by treating the fabric in the web with gutta-percha solution while passing through the machine shown in Figs. 1 and 2, and then in folding the fabric into the required breadth and the requisite number of plies or thicknesses, with or without the addition of a layer or layers of gutta-percha or gutta-percha compounds, preferably between each alternate layer of the canvas and on one side of the complete belt, which would give the whole 60 greater flexibility and gripping-power, as indicated in Figs. A² to A⁵.

Referring to Figs. 1 and 2, the fabric, A, is first rolled on a beam, B, mounted in bearing-brackets B' in the front part of the framing 7c B² of the machine, and led forward under and over the guide-rollers D D, carried in bearings in the same frame, behind the beam B, over the top of a table, D', down or under three guide-rollers, D'', within the close box D², up 75 in front of a heating fire-grate, C, over and horizontally along the series of pinned or spiked and plain guide-rollers D''' D³, carried in journal bearings or hanging frames E, supported from the beams E', and standards E'' 80 under the roof of the apartment, and all enclosed within sheet-iron chambers E² E³, throughout the length of the machine, to prevent the flames running along the web A of fabric should it take fire while being heated 85 in front of the grate C.

I apply the gutta-percha solution to the fabric, A, by brushing or otherwise while it is slowly traversed in a continuous length over the table D', and I insure the thorough penetration of the solution into the pores of the fabric, A, by causing the fabric to travel in front of a fire, C, or it might be other source of heat, which has the effect of driving this adhesive solution of gutta-percha into the 95 fibers and interstices of the cloth, A. The fabric, A, is thence carried over a series of spike-rollers, D''', and other guide-rollers, D³, for a considerable length to give ample time 100 for the evaporation of the naphtha or sol-

vents and drying of the gutta-percha solution before being returned over the under guide-rollers, D⁴, and finally wound into a roll on a reel or beam, as at H.

- 5 The arrangement for so winding or beaming the web A of canvas, whether dressed or coated on the one side or on both sides with the solution of gutta-percha, as described, is shown as driven from an overhead motive-power shaft, F, carried by hangers E⁴ from the beams or joists E' of the roof and driven by a belt, F', passed over a small pulley on the shaft F and a cone speed-pulley, F², below on a shaft, F'', carried in journal-bearing brackets F''', secured to the standards E'' of the framing. The web of fabric, A, to be beamed is passed down under a loose revolving adjustable roller, G, carried by adjustable screws and guides at G', and passed up over 10 the roller G² in front of this roller G onto the beaming-roller H, carried in journal-bearing standards H', actuated by a belt, G³, from a pulley on the spindle F'', all so as to wind or beam it at a very slow rate, as indicated by the arrows in Fig. 1. The coated beam of fabric, A, is wound over a trough, H'', provided with a water pipe and tap, H², so that this may be instantly filled with water should the naphtha and gutta-per- 15 cha of the fabric by any accident take fire, and a winding-handle, H³, is mounted on the spindle of the beam or roller H, so as to wind the fabric up by hand when anything goes wrong with the winding mechanism and rotate it within the water, when this is required to extinguish the fire. The rolls of fabric, A, when so coated and finished on the one side, are then removed from the beam H and placed on the beam B in a re- 20 verse manner. The cloth, A, is then again unwound from the beam B and submitted to the same operation of brushing and coating on the reverse side, and also subjected to the rays of the fire, C, so as to have the inner 25 side of the fabric A coated all as and in the same manner as the first side, and after passing over the series of rollers D''' D³ is wound again into a roll on the beam H, completely coated on both sides, ready for the next operation of being cut into the widths desired for making the belts, as will hereinafter be described.

In passing to the fire, C, the fabric, A, is carried through a flame-trap, D², which consists of a shallow box lined with or formed of sheet-iron, with slits at the ends e large enough merely to permit the free passage through it of the fabric, A, and then, after passing up from the fire, C, it is led along the upper part of the apartment through similar long flame-traps or close chambers, E² E³, with close slits e at their ends for allowing the fabric to pass, but prevent the extension of the flame to the main body of the fabric, A, in the event of the solution catching fire where exposed to the heating process. A fine wire-gauze screen would be interposed at C' C' between the

grate-fire, C, and the upward traversing prepared vertical face of the canvas, A A, to prevent sparks from the fire getting at the naphtha and gutta-percha solution of the prepared face to ignite this. The darts indicate the radiation of heat out from the fire, C, toward the prepared fabric, A. The rolls of fabric, A, so prepared on both sides with gutta-percha solution, are removed from the beam or roller H of the beaming mechanism of the machine shown in Sheet 1 and placed on the beam or spindle I, carried in bearing-brackets I' at one end of the frame I² of the cutting-machine shown in Figs. 7, 8, and 9 of Sheet 2, so as to be cut into the strips or widths, preferably twice the breadth of the belt required, and suitable for being folded and rolled into the exact width of the belts 80 to be made from these strips.

The web A, as indicated by the arrows, is passed from the reel-beam I over the guide-roller i of the table I³ and under and over the guide-rollers i' i² at the center of the table 90 and on each side of the cutting knife or knives J J', carried in a slotted transverse rail, J², and then over the guide-roller i³ at the other or delivery end of the machine, where the man stands and pulls the fabric 95 through the machine and between the angle-iron guides j j', secured at each edge of the web A of fabric, which keeps it parallel while traveling through the machine and the guide-rollers and cutters; or the strips might be 100 wound onto a roller at this end I''' of the machine as they were cut and drawn forward by being wound onto the roller. Slotted guide bars or frames j² j² are secured across the table I³ below the guide-rollers i' i², for securing 105 the slide-guides j j' at any width to suit that of the fabric being cut, the small guide-rollers, i' i² working through holes in the vertical angled sides of the guides j j', carried in journal-bearings at their ends. I cut the so- 110 lutionized fabric, A, longitudinally, as described, into strips preferably of twice the width (or it might be of three or a greater number of times) of that of the belt required, as dotted at a a', and fold them to the desired 115 width, A A', as shown in the cross-section diagram of a belt, Fig. A'. In general, I find it advantageous to employ these flat bands made up of double plies of the "solutionized" 120 canvas, as just described and shown. I fold the fabric in this manner by passing it through a short tube or orifice, K, (shown particularly in the detailed views, Figs. 5 and 6,) and inserted in a transverse bar of wood, L, which is secured by pinching-screws 125 L' in the frame L² over the table L³ at the entering end of the rolling and pressing mechanism. (Shown particularly at M M in the general arrangement, Figs. 3 and 4.) A screw-pin, k, is fitted in the tube K, having 130 at its inner end a folding disk or tooth, k', which divides and folds the fabric A evenly and regularly as it is entered by hand and drawn in afterward by the drawing and

pressing rollers $m m'$, and indicated in dotted lines in Fig. 6, so that it is delivered in a folded state to the first set of pressing and drawing rollers $m m'$, with the edges of the fabric forming a seam or joint, a'' , on the one side either in the center or somewhat to one side of the width of the band, as indicated in Fig. A', and so that when a belt is made of two double plies the seams are placed in the center—
 5 that is, adjacent to each other—but breaking bond in the width of the band, as indicated at $a'' a''$ in Fig. A³, showing a section of a quadruple or four-ply belt. These belts or flat bands of double thickness, as indicated in Fig. A', may by one method be formed from the fabric, A, so treated with gutta-percha solution by passing the strip A, cut to the width required, through the close heating chamber or box P to soften it, and then
 10 fold it by passing it while the solution is soft through the said folding or doubling guide-tube K, and then through the pressing-rolls $m m'$ to form or compress it to the requisite breadth and thickness, as will hereinafter be
 15 more particularly described. I prefer, however, by these improvements to form the belts or flat bands of alternating double layers of solutionized cloth and gutta-percha compounds—that is, by feeding in a thin layer,
 20 a^2 , of a tough elastic compound of gutta-percha on the top of the joint surface $a a'$, with a large proportion of "balata" in it in a heated plastic state while passing the doubled belt shown in Fig. A' a second time through the
 25 machine, leaving this layer of gutta-percha compound all along its upper surface, as indicated at a^2 , and which answers for the lighter form of belts, only having the solutionized canvas on the one side A A', while
 30 having the gutta-percha compound, a^2 , on the other side, and either side may be made to act on the pulleys, as desired; but when stronger belts are required I prefer to make them by joining two of these double thicknesses together (indicated in Fig. A²) by passing them in a heated state through the machine and between the rollers $m m'$, which thus gives the double ply of canvas, A, first secured together by the solution, and then the
 35 succeeding double plies secured together by a layer of the said elastic compound mixture, a^2 , alternately between the double layers A, as indicated in the transverse section, Fig. A³. When still stronger belts are required,
 40 they are made of three or it might be more plies of these doubled thicknesses of solutionized canvas, A A', and alternate layers of gutta-percha compound, a^2 , as shown particularly in Figs. A² A³ A⁴.
 45 The general construction and arrangement of the parts of the machine or mechanism shown in Figs. 3 to 6 on Sheet 2 for so heating, doubling, and compressing or rolling these strips of prepared canvas, cut to their
 50 widths, into the belts or flat bands, as described, consist all as follows: Of a fire-grate, C, erected at one end of the apartment in front

of an air-heating box, C², the fire directly heating the front side of the box, while a portion of the flames and heated products of combustion pass from the lower part of the fire under the box to heat it and then pass up a flue, C'', close to the back of the box, so as to heat this also. The air to be heated is led in through a pipe, g, and undulates through passages g' in the box, divided off by plates g'', and is led off by the pipe g² in a highly-heated state by the small double branch pipe g³ into the lower part of the close heating-chamber P, preferably formed of wood lined with sheet metal and erected on a framing, P', close to the heating-fire. The strips or widths of canvas, A, to be folded and doubled, as described, are mounted on spindles and reels R in journal-brackets R' in the lower part of the frame 85 of the doubling, rolling, and compressing machine M. The strips of canvas, A, are led from the reel R up over a guide bar or roller at Q through a slit, P'', in the lower part of the heating-box P, forward through a slit, 90 P''', in the front end of the box, over the guide-roller Q', back through the upper division, P², of the heating-box P to soften the solution, and through another slit, P'''', over the slit P'' in the rear end of the box above the 95 level of the table L³ of the rolling and pressing machine M to and through the first pair of rollers $m m'$, and then through the others in succession, four sets of which are shown in the machine M. These rolls $m m'$ are preferably finely corrugated annularly with sharp ridges and grooves to assist in the better compression of the canvas, A, and its solution while passing through them. The lower set of rollers, m, have long spindles and are mounted 100 in bush-bearings m'' below the surface-level of the table L³ in the main frames M, and in a supplementary framing, M', carried on brackets M'' on the back frame, M, of the machine. Each spindle of the lower roller, m, 105 has mounted on its back end a screw-wheel, p, actuated by a screw, p', on the first motion-shaft p², mounted longitudinally in bush-bearings M''' in the brackets M'', having on its overhanging end a fast and loose pulley, 110 p³, actuated by a cross-belt, p''', from band-pulleys on a main driving-shaft carried in the upper part of the building, but not shown in the drawings, this belt p''' being shifted by a belt fork and lever, p⁴. The 115 lower rollers, m, are mounted to carry the band A just slightly above the surface of the table L³, and have small spur-pinions o mounted on them, which gear into larger pinions, o', mounted on studs projecting from the 120 back frame, M, gearing into wheels o'', mounted on corresponding studs in brackets projecting up from the back frame, M. These wheels o'' gear into small pinions o² on the upper rollers, m', so as to actuate them at various heights above the lower rollers, m. The 125 upper roller, m', of the first set of rollers is simultaneously raised and lowered at both ends to the desired height by screw-spindles 130

m''', connected to their slide-bushes *m²*, mounted in their vertical slide-guides *m³* by a horizontal hand-spindle, *n*, carried in cap-bushes *n''* on the upper ends of the spindles *m'''*, through beveled or miter wheels *n'* on it and on the upper end of these screw-spindles *m'''*, all so as to regulate the pressure that will be given to the prepared strips *A* passing through them and also regulate the thickness 5 of the layer of gutta-percha compound, *a²*, being fed in by an attendant over the strip in front of these rollers in a heated and plastic state. The upper rollers, *m'*, of the other three sets have spiral springs *n²* mounted 10 above their bushes *m²*, with pinching-screws *n³* in their slide-guides *m³* for regulating the pressure that is to be put on these rollers, respectively, over the prepared strip or strips *A* passing through them. The belt *A* thus prepared passes in a firm and nearly cooled state 15 onto the endless traveling band *N*, actuated by the end roller, *N'*, through a pulley and belt, *N²*, and passed over the carrying and guide rollers *N''* to the extreme delivery end 20 roller, *N³*, from which the finished band is wound onto a reel, *A³*, on the spindle *S'* of the revolving winding table or disk *S*, actuated from the roller *N³* by the cross-belt *S''* and friction-pulley *S²*, acting on the edge of the 25 disk *S*. The thin layer *a²* of gutta-percha fed on by the attendant over the top is pressed out sidewise by the rollers, and the superfluous gutta-percha compound is afterward trimmed or dressed off along the edges even 30 with the edges of the canvas by a hot blunt knife, either by hand or automatically, in front of the set of rollers *m m'*, when the band would then be ready for use as light belting 35 in the form shown in Fig. *A²*.

40 In forming belts of great strength two or more composite flat bands, *A a²*, so formed, as shown in Fig. *A²*, are united together by mounting them in separate rolls or reels *R* in the bearing-brackets *R'* under the table-frame *M* and passing them through the heating-chamber or box *P*, separated by moistened guides or rollers, so as not to touch each other, to soften the solution on one side of the band *A* and the layer of gutta-percha 45 compound, *a²*, on the other side, the bands being guided from the heating-box into and through the rolls *a a'*, which, by pressing the gutta-percha, *a²*, of the one band *A* in contact with the solutionized fabric of the other band 50 *A*, cause the bands to adhere firmly and form a single strong band, *A*, as indicated at Figs. *A³ A⁴*; or, a three-ply belt might be so formed, as indicated at Fig. *A⁵*, out of one width, *A*, of canvas, coated on the one side with the 55 gutta-percha compound, *a²*. The composite belts so produced have a surface layer of the gutta-percha compound, *a²*, between each double thickness of the prepared canvas and a layer on the one outside surface and a surface 60 of solutionized canvas on the other outside surface, either of which outside surfaces may serve as the driving-surface. In cases where 65

the surface thickness, *a²*, of gutta-percha compound is not desired I combine together a composite belt of one or more plies and a solutionized belt by passing them through the heating-chamber and through the pressing-rolls, with a sufficient thickness of solution on the surface to be united as to insure their complete attachment by passing through the 70 set of pressing-rollers.

Solutionized belts and composite belts, formed in the manner described and shown in cross-section in the several figures *A'*, *A²*, *A³*, *A⁴*, and *A⁵*, are, I find, highly superior in 75 tensile strength and transmitting and gripping power on their pulley-surfaces as compared with the cotton or the rubber-cloth belting heretofore in use, the warp and weft of the canvas or other strong cotton fabric employed 80 being greatly bound together by the fibers being thoroughly impregnated with the gutta-percha solution. The slight heating of the belts by the friction of driving has the effect of sufficiently softening the solution or the 85 gutta-percha mixture, *a²*, on the acting side to give a great gripping action on their driving-pulleys, and so prevent all slipping.

Instead of forming the solutionized belts *A* by coating, heating, and treating the woven fabric and then cutting, folding, and rolling the same, as described, I may form such belts from ordinary sewed cotton belts stitched together by thoroughly impregnating such belts with gutta-percha solution from both sides, 90 and I may form composite belts therefrom by superadding a layer or alternate layers of the said tough yielding or elastic gutta-percha compound, *a²*, in the manner before described 95 in reference to the forming of my improved 100 belting, Figs. *A'* to *A⁵*, without sewing.

The gutta-percha or gutta-percha compound employed for forming the layers *a²* in the manufacture of these belts or flat bands should be of a tough, flexible, and elastic character, 110 such as the mixture of gutta-percha with balata, (which is the gum of the "bullet" tree,) or of selected tough gutta-percha or other equivalent which would give the soft, 115 flexible, and slightly-elastic character described and desired for the purpose of these improvements and be of a tensile strength nearly equal to that of the canvas in proportion to their relative thickness. My new or improved flat belts or bands so formed are 120 finished by stretching them while the gutta-percha and its compounds are slightly heated to the best tensile strain that the canvas or fabric will bear without injury, and allowed to cool and dry under the strain, so that these 125 belts may stretch little or none when put to use. The object of introducing the layers of gutta-percha compound, *a²*, between the layers or double layers of canvas or other strong fabric in these belts or flat bands is to give them 130 flexibility and gripping-power and a tensile strength equal to the canvas, and which cannot well be obtained by the mere use of layers of pure gutta-percha or gutta-percha solution

with the cotton cloth, and which has the further effect of preventing the canvas or fabric from wearing or cracking, as ordinary cotton or canvas belts as heretofore made 5 are liable to do. When these belts or flat bands are required for the driving of power-looms or other textile machinery or purposes where a very regular and delicate gripping and driving action is required, suitable only 10 for the power to be transmitted and which would slip when extra strain was brought against it, and would yet maintain its maximum gripping effect without glazing or slipping, I by a further improvement attach a 15 layer or thickness of serge or other woolen-surface fabric on the working or gripping side of the belts by passing both through in a heated state between the pressing and gripping rollers shown in Figs. 3 to 5 on Sheet 2 20 of the drawings. When these belts or flat bands are to be used for hauling or other purposes—such as traces for carriages or for the drawing of agricultural implements—they would preferably be coated on both sides with 25 gutta-percha before being finished to protect the canvas from the weather and from wear and tear. Other beaming arrangements than those shown at F F² G G² H in Figs. 1 and 2 for winding the finished solutionized webs of 30 fabric may be used, and fanners or exhausters might be used for blowing or drawing off the naphtha-vapors rising from the solutionized surface of the fabric or from the boxes D² E² E³ it is passed through, although these are not 35 shown in the drawings. Although the heating-box P P² in Figs. 3 and 4 is shown as horizontal, it might be arranged vertically,

and the various strips or bands A to be heated in passing through it for being rolled into a composite belt would in either case be kept 40 separate by flanged rollers or other equivalent guides, preferably hollow and perforated and covered with cloth over them to retain moisture, so as to prevent the belts touching each other or sticking to the guide-rollers. 45

What I claim is—

1. The herein-described method of preparing flat belts or bands, said method consisting in impregnating a web of canvas or other fabric with a gutta-percha solution, then partially heating it, folding the web into a belt or band of the desired width, heating the folded web, and passing it between pressure-rolls, substantially as set forth. 50

2. The herein-described method of making 55 composite flat belts or bands by first impregnating webs of canvas or other fabric with a solution of gutta-percha, then subjecting the impregnated webs to heat, then folding the webs into belts or bands of the desired width, 60 and then applying to the belts or bands thus impregnated and folded elastic layers or sheets of gutta-percha compound, substantially as set forth.

In testimony whereof I have signed my 65 name to this specification in the presence of two subscribing witnesses.

ROBERT DICK.
